UNITED STATES PATENT OFFICE.

ARMISTEAD C. CRUMP, OF NEW YORK, N. Y.

PASTE-TUBE.

1,266,413.

Specification of Letters Patent. Patented May 14, 1918.

Application filed June 26, 1917. Serial No. 176,996.

To all whom it may concern:

Be it known that I, ARMISTEAD C. CRUMP, a citizen of the United States, and a resident of the city of New York, borough of 5 Manhattan, in the county and State of New York, have invented a new and Improved Paste-Tube, of which the following is a full, clear, and exact description.

This invention relates to containers of the 10 flexible tube type especially adapted for containing paste, although it is not limited to this use.

The object of the invention is to provide a new flexible or collapsible container, and 15 also a new method of filling the same.

A more specific object of the invention is the provision of a single-piece flexible container made of transparent celluloid in which the material can be filled through the 20 mouth instead of through the open bottom, as is commonly the case. To carry out this method the tube is closed at the bottom and the body of the tube is then collapsed, and while in this condition the paste or other 25 material is forced in through the mouth under pressure, whereby the tube is distended, and since the wall of the tube is transparent it is possible to ascertain whether or not the full charge is supplied. 30 The tube being of celluloid the contents cannot be affected deleteriously, as is liable with a metal tube.

For a more complete understanding of the 35 invention reference is to be had to the following description and claims taken in connection with the accompanying drawing which illustrates certain embodiments of the invention and wherein similar characters of reference indicate corresponding parts in all 40 the views, in which—

Figure 1 is a side view of a tube;

Fig. 2 is a view taken at right-angles to Fig. 1, with a portion in section;

Fig. 3 is a similar view showing the bottom closed in a different manner from that in Fig. 2;

Fig. 4 is a sectional view on the line 4—4, Fig. 1, showing the tube in normal condition;

50 Fig. 5 is a sectional view showing the tube collapsed;

Figs. 6 and 7 are perspective views of the interlocking strips for closing the bottom of the tube;

55 Fig. 8 is a perspective view of the clip

for binding the closed bottom of the tube shown in Figs. 1 and 2;

Fig. 9 is a sectional view on the line 9—9, Fig. 2; and

Fig. 10 is a detail sectional view of a 60 modified form of the closed bottom of the tube.

Referring to the drawing, 1 designates the body of the tube, which is made from tubular stock of celluloid which is transparent and pliable. The tube is formed at one end into a neck 2 and mouth 3, both of which are yielding or collapsible, which feature enables the contents of the tube to be forced out to the last drop. The bottom of 70 the tube may be closed in any suitable manner, as for instance, by cementing the two opposite sides of the tube together as at 4, Fig. 3, or two semi-circular sealing members 5 and 6, as shown in Figs. 6 and 7, 75 may be employed. The member 5 has a longitudinal tongue 7 which is adapted to enter in a longitudinal groove 8 in the member 6. These members are made of celluloid, and the bottom edge of the tubular 80 body, while the latter is in circular cross-sectional shape, is cemented to the members 5 and 6, and then the latter are flattened out so that the two members interlock. These members can be cemented together, and further security can be obtained by applying a metal or other clip 9 which is constructed as clearly shown in Fig. 8. The mouth of 85 the tube can be closed by a stopper of any suitable construction.

In Fig. 10 is shown a modified method of closing the bottom of the tube. One-half of the tube has a groove 10 on its inner surface and the other half has a tongue 11 which engages in the groove, and a metal or other 90 clip 12 clamps the two halves of the tube tightly together, said clip being of U-shaped cross-section and having its opposite walls shaped to fit the outer surfaces of the walls of the tube, whereby the clip is prevented 95 from becoming loose or pulling off.

To fill the tube the latter is flattened so as to force out the air, and then while in this condition the mouth of the tube is connected with a nozzle, tube or other supply device 105 through which material is forced under pressure into the tube. Since the wall of the tube is transparent it is easy to ascertain whether or not the proper supply of material is delivered to the tube.

From the foregoing description taken in connection with the accompanying drawing, the advantages of the construction and method of operation will be readily understood by those skilled in the art to which the invention appertains, and while I have described the principle of operation, together with the article which I now consider to be the best embodiment thereof, I desire to have it understood that the article shown is merely illustrative and that such changes may be made when desired as fall within the scope of the appended claims.

Having thus described my invention, I claim as new and desire to secure by Letters Patent:

1. A tube of the class described comprising a resilient tubular body having a contracted neck terminating in a mouth, said neck and mouth being resilient and adapted to return to their original shape after being compressed.
2. A tube of the class described comprising a resilient tubular body having a contracted neck terminating in a mouth, said

neck and mouth being resilient and adapted to return to their original shape after being compressed, said neck, body and mouth being in one piece.

3. A tube of the class described comprising a tubular body, clamping strips having longitudinal tongue and groove interlocking means for closing one end of the tube, and a clip engaging over the strips to hold the same together.

4. A tube of the class described comprising a tubular body, clamping strips having longitudinal tongue and groove interlocking means for closing one end of the tube, and a clip engaging over the strips to hold the same together, said clip having inwardly extending flanges engaging the said strips to retain the clip in place.

5. A tube of the class described including as a one-piece article a body, neck and mouth made of resilient, transparent material, the neck and mouth being compressible as well as the body.

ARMISTEAD C. CRUMP.
